DOOR LOCK

Homer E. Malone, Minneapolis, Minn.

Application April 27, 1934, Serial No. 722,660

10 Claims. (Cl. 70—29)

This invention relates to new and useful improvements in door locks, generally, and more particularly to door locks of the character adapted for use in private homes, and the like.

5 An object of the invention is to provide a door lock which is neat and attractive in appearance; comprises few working parts; is positive and safe in operation, and may readily be mounted in a door without cutting away large portions of the 10 door, and which is provided with means for locking it whereby it cannot be opened from the exterior of the building by an unauthorized person; and which is simple and inexpensive in construction whereby it may be manufactured at a comparatively low cost.

The invention further concerns itself with the provision of a door lock comprising a bolt mounted for sliding movement within the door, and having a hollow handle secured to the door in fixed relation, and provided with a latch member mounted for swinging movement into and out of said handle, said latch member having an operative connection with the bolt and being so arranged that when the handle is grasped, the locking bolt will be retracted to thereby permit the door to be opened.

Other objects of the invention will appear from the following description and accompanying drawings and will be pointed out in the annexed claims.

30 In the accompanying drawings there has been disclosed a structure designed to carry out the various objects of the invention, but it is to be understood that the invention is not confined to the exact features shown as various changes may be made within the scope of the claims which follow.

In the drawings:

Figure 1 is an elevational view partially in section showing the general construction of my improved lock;

Figure 2 is a sectional plan view on the line 2—2 of Figure 1, showing the means for operating the locking bolt when the latch members are actuated;

Figure 3 is a detail sectional view on the line 3—3 of Figure 2;

Figure 4 is a vertical sectional view on the line 4—4 of Figure 1, showing the means for locking one of the slides against movement;

Figure 5 is a vertical sectional view on the line 5—5 of Figure 1, showing the construction of the lock at the inner side of the door;

Figure 6 is an exterior view of the lock as seen from the inner side of the door; and

Figure 7 is a detail sectional view on the line 7—7 of Figure 1.

The novel lock herein disclosed comprises a pair of handles 2 and 3, the former being adapted for use on the interior side of the door and the latter on the exterior. The handles terminate at their lower ends in lugs or projections 3' and 4, respectively, adapted to receive a suitable screw 5 received in threaded engagement with the lug or projection 4 of the handle 3. Suitable facing 10 plates 6 are seated against the opposite sides of the door 7 and have apertures therein adapted to receive the screw 5. Spacers 8 are shown provided between the inner surfaces of the plates 6 and the adjacent faces of the door 7 to prevent distortion 15 of the plates, when the bolt 5 is tightened. By arranging the screw 5 as shown, it cannot be removed from the exterior of the door, as will be noted by reference to Figure 1.

The upper ends of the handles 2 and 3 are provided with housings 9 and 11, respectively, which contain the mechanism of the lock, which will subsequently be described. Each handle has at its upper end, an enlarged head or flange 12. These heads are seated against the face plates 6 25 and have apertures therein adapted to receive screws 5 similar to the one provided at the lower ends of the lock.

A cylindrical casing 13 is mounted in a suitable bore or cavity 14 provided in the door, as best 30 shown in Figures 2 and 3, and has a face plate 15 secured to one end thereof which is received in a recess 16 provided in the edge of the door. The face plate 15 is preferably rectangular in configuration and may be secured to the door by suitable 35 screws, not shown.

A locking bolt 17 is mounted within the casing 13 and has a head 18 provided with a beveled face 19, as is customary in bolts of this type. The main body portion of the bolt 17 is relatively 40 smaller in diameter than the head 18, and has a suitable spring 21 coiled thereabout, one end of which is seated against a shoulder 22 at the inner end of the head 18, and the opposite end of which is seated against a retaining block 23, 45 shown in Figures 2 and 3. The locking bolt 17 is forked at its inner end to provide a pair of spaced legs 24, and the retaining block 23 is supported in the space between the legs 24 and has its opposite end portions notched, as indicated at 25 in Figure 2, and suitably secured to the walls of the casing 13 by inwardly bending portions thereof into the notches shown at 25. The wall of the casing 13 is provided with oppositely disposed, elongated openings or slots 26, 55

in which portions of the retaining block 23 are received, as will be clearly understood by reference to Figure 2.

The inner end of the locking bolt 17 is guidingly supported within the casing 13 by means of a roller 27, rotatably mounted on a pin 28 secured in the spaced legs 24 of the bolt. The diameter of the roller 27 is substantially the same or slightly less than the inside diameter of the casing 13, and the length of the pin 28 is substantially equal to the diameter of the roller 27, whereby the inner end of the locking bolt is axially guided in the casing when the bolt is relatively moved therein. A relatively smaller roller 29 is mounted 15 in the legs 24 of the locking bolt adjacent to the roller 27, and is adapted to be engaged by the mechanism for operating the bolt, which will next be described.

The means for actuating the locking bolt 17 is best shown in Figures 1 and 2, and comprises a slide 31, the inner end of which is preferably shaped as shown in Figure 2, and has a cam face 32 adapted to engage the roller 29. It will be noted that the inner end portion of the slide 31 passes through the slots 26 provided in the wall of the casing 13, and through the space provided between the legs 24 of the locking bolt and is normally engaged with the abutment block or member 23, as clearly shown in Figure 2. 30 The outer end portion of the slide 31 has an aperture 33 therein adapted to receive a small lug or projection 34, provided upon the upper end of a lever 35, which is pivotally supported in the lower portion of the handle 3 by means of a suitable pin 36. The lever 35 is preferably shaped as shown in Figure 2, and is adapted to be pressed or swung into the handle when the latter is grasped, as indicated by the dotted lines 37 in Figure 1.

40 A suitable spring 38 is mounted within the handle 3 and has its upper end bearing against a wall thereof. The lower offset end portion 39 of the spring 38 is engaged with the reduced central portion of the pin 36, as best shown in Figure 7, whereby it cannot accidentally become disarranged within the handle. The spring 38 constantly urges the lever 35 inwardly, and, at the same time, functions as a retainer for the pin 36, whereby the latter cannot be removed 45 from the handle. The lever 35 has its upper end portion 41 extending inwardly and normally engaging the face plate 6, as shown in Figure 1, whereby when the lever is locked against movement, the upper end portion 41 thereof provides a closure for the locking mechanism, as will 50 readily be understood.

The handle 3 is provided with a suitable lock, generally indicated by the numeral 42, mounted in the housing 11. This lock may be of any well-known construction, and is adapted to be actuated by a suitable key 43, as is customary.

In the drawings, the lock 42 is shown comprising an outer casing 44 having a cylindrical member 45 mounted therein and suitably secured 60 to the casing 44 by suitable means such as indicated at 46. A key receiving member 47 is mounted for relative rotation within the tubular member 45, and is shown provided with the usual tumbler pins which cooperate with similar pins provided in the member 45 to lock the key receiving member 47 against rotation, when the key is removed from the lock.

70 A locking plate 48 is mounted at the inner end of the cylindrical casing or shell 44 and has a lug 49 projecting outwardly through an opening

51 in the casing 44, and adapted to be received in a notch 52 provided in the slide 31, as shown in Figures 1 and 2, thereby to lock the slide 31 against longitudinal movement. The locking plate 48 is retained in the casing 44 by inwardly bending the walls of the latter to provide an inwardly turned flange 53. A circular disk 54 is shown seated against the inner face of the locking plate 48, and is secured thereto by a notched plate 55 which also is secured to the locking plate 48 by such means as rivets 56. The notched plate 55 is spaced from the adjacent end of the tubular member 45, as shown in Figure 1, and a suitable torsion spring 57 has one end secured to the notched plate 55 and locking plate 48, and its opposite end to the tubular member 45. This spring normally retains the lug 49 of the locking plate 48 in locking engagement with the slide 31, as shown in full lines in Figure 4. The inner end of the key receiving member 47 is interlocked with the plate 55 in the usual manner, so that when the member 47 is relatively rotated by means of the key 43, the locking plate 48 will be correspondingly rotated to move the lug out of locking engagement with the slide, as indicated by the dotted lines in Figure 4.

The key receiving member 47 and its associated parts, above described, are confined within the casing 44 in substantially the same manner as an ordinary cylinder lock, and said lock is shown secured in position in the housing 11 of the holder 3 by a small screw 58, received in threaded engagement with the tubular member 45. The head of the screw 58 is received in an aperture provided in the lower wall of the housing 11. The lock is inserted into the housing 11 before the handle 3 is secured to the door.

Means is also provided whereby the bolt 17 may be actuated from the inside of the building by simply grasping the handle 2. To thus operate the lock, a similar lever 59 is pivoted to the handle 2 by a similar pivot pin 36, and its upper end has a lug or projection 61 received in an aperture 62 provided in a slide 63, shown composed of two parts suitably secured together by such means as welding or riveting. The parts of the slide 63 are spaced apart at the inner end of the slide, as best shown in Figure 1, to receive therebetween the slide 31. The inner ends of the spaced parts of the slide 63 are provided with corresponding cam faces 64, similar to the cam face 32 of the slide 31. The cam faces 64 are adapted to engage the roller 29 in a manner similar to the cam face 32 of the slide 31, as clearly illustrated in Figure 2. Thus, when the lever or latch member 59 of the handle 2 is pressed into the handle 2 by a person grasping the latter, the slide 63 will be actuated to operate the bolt 17 and thus release the door. By thus providing a separate slide for each handle, said handles may be operated independently of each other to open the door.

It is also to be noted that when the lock 42 is actuated to lock the slide 31 against movement, the slide 63 may be freely operated by movement of the lever or latch 59, whereby the door may readily be opened from the inside of the building, whereas, it cannot be opened from the outside, unless the lock 42 is actuated by the key 43 to release the slide 31.

Means is also provided whereby the slide 31 of the outer handle 3 may be locked against movement from the interior of the building with-

out operating the lock 42. Such means is best shown in Figure 1, and comprises a cylindrical plug 65 received in the bore of the housing 9 of the handle 2. This plug has a reduced portion 66 received in an aperture 67 provided in the housing 9, and preferably has its projecting end portion 68 flattened or so shaped that it may be conveniently rotated by grasping it with the fingers.

10 An operating member or bar 69 operatively connects the plug 65 to the locking plate 48, whereby when the plug 65 is relatively rotated in one direction, the locking bar 69 will release the locking plate 48, and permit the spring 57 to move it from the dotted to the full line position, shown in Figure 4, whereby the slide 31 is locked against movement. When thus positioned, the door cannot be opened from the exterior of the building by merely grasping the handle 3, as the lever or latch member 35 thereof will be locked against movement. To release the lever 35 of the handle 3 of the door from the interior of the building, the finger grip 68 of the plug 65, which may be termed a "night lock", 15 is rotated from the full to the dotted line position shown in Figure 1, or substantially 90°, whereby the bar 69 will rotate the locking plate 48, against the tension of the spring 57, to its unlocked position, indicated in dotted lines in Figure 4, whereby the door may be opened from either side. A suitable plate 71 is seated against the inner end of the plug 65, and has a depending portion 72 received between the opposite walls 20 of the lower portion of the housing 9, to thereby lock the plate 71 against rotation. A suitable aperture 73 is provided in the plate 71 to receive the locking bar 69. This aperture is of such size and shape as to permit the locking bar to be rotated substantially 90°, the walls there- 25 of providing abutments for said bar to thereby limit its rotary movement in both directions.

A suitable compression spring is shown interposed between the face plate 6 and the plate 71, and has its opposite ends seated against suitable 30 thrust washers which, in turn, are seated against the face plate 6 and apertured plate 71, respectively, as best shown in Figure 1. The inner end of the plug 65 is shown provided with two sockets 74 adapted to selectively receive a detent or 35 raised portion 75, which may be provided upon the plate 71, to thereby secure the plug 65 in either locked or unlocked position.

The parts of the night lock include the plug 65, finger grip 68 and bar 69, all of which parts are 40 inserted into the housing 9 before the handle 2 is secured to the door, whereby the parts thereof cannot be tampered with when once assembled as shown in Figure 1.

As indicated in Figure 4, the locking plate 48 of the lock 42 does not rotate 90° when moved from locking to unlocking position, or vice versa. The key 43 and night lock 68, however, are arranged to rotate substantially 90°. This is brought about by reason of the unique shapes of 45 the openings 50 and 60 in the locking plate 48 and plate 55, respectively, and further, by reason of the openings 73 provided in the anchor plate 71, the radial walls of which provide limit stops for the bar 69. By shaping the apertures 60 of 50 the plate 55, as shown in the drawings, the tongue 76 of the key receiving member 47 of the lock 42 will move idly for about two-thirds of its movement, or approximately 50°, before it engages the radial walls of the apertures 60, after which 55 the plate 65 will rotate therewith until the key

receiving member 47 has completed its full movement of approximately 90°. Such movement of the plate 55 will cause a similar movement to be imparted to the locking plate 48, whereby the lug 49 will be moved from the full to the dotted line 5 position, shown in Figure 4, or into unlocking position.

The operation of the night lock 68 is quite similar to that of the key receiving member 47, as it, too, must be rotated substantially 90°, or from 10 the full to the dotted line position shown in Figure 1 in order to move the lug 49 out of locking engagement with the slide 31. The idle movement resulting because of the shapes of the slots 50-50 and 73, is provided primarily for the purpose of increasing the degree of rotation of the key 43 and also the night lock 68, whereby they are rotated substantially 90° to lock or unlock the door.

When the night lock 68 is in unlocking position, 20 as indicated in dotted lines in Figure 1, the door may be opened from either side, as the lug 49 will then be in its unlocked position, indicated in dotted lines in Figure 4, whereby the levers 59 and 35 may be freely operated.

When the night lock 68 is turned to the full line position, shown in Figure 1, the torsion spring 57 will move the lug 49 into locking engagement with the slide 31 whereby the door is locked from the exterior, but may be conveniently opened 30 from the interior, as the lever 59 is always in unlocked position. Rotation of the night lock 68 does not impart any rotation to the key receiving member 47. To unlock the door from the exterior, the key 43 is inserted into the key-receiving 35 member 47 and the latter rotated 90°, whereby the lug 49 will be moved out of locking engagement with the slide 31. As a result of the key receiving member 47 being influenced by the action of the spring 57, which tends to rotate it 40 in a direction to move the lug 49 into locking engagement with the slide 31, the key 43 must be manually held in its unlocked position, in order to hold the lug 49 out of engagement with the slide 31, and while thus held, the operator may 45 grasp the handle 3 and actuate the lever 35 to open the door. As soon as the key 43 is released, the spring 57 will rotate it in a direction to move the lug 49 into locking engagement with the slide 31, in which position said lug is normally retained 50 by said spring. The key must be rotated to the position shown in Figure 1 before it can be withdrawn from the key receiving member 47.

The novel lock herein disclosed is very simple and inexpensive in construction, and may be manufactured in large quantities at a very low cost. It is neat and attractive in appearance, and comprises few parts, all of which are so arranged as to provide a lock which is substantially fool-proof in operation. When the operating levers 35 and 55 of the handles 3 and 2, respectively, are in their normal positions, as shown in Figure 1, it is impossible to gain access to the interior of the lock. It is also to be noted that the screws which secure the lock to the door are not visible from 60 the exterior or outside of the door, thereby making it impossible for an unauthorized person to remove the lock in an attempt to gain access to the building. It is further to be noted that the operating levers 35 and 59 cooperate with the 65 handle portions 3 and 2 to complete the formation thereof, and when in normal positions, as shown in Figure 1, cause the handles to appear very rugged and substantial, and of comparatively 70 large cross-section at their upper portions.

The levers 35 and 59 are so formed as to provide a very convenient grip, and by connecting them to the slides 31 and 33, as herein shown, the bolt 17 of the lock may be conveniently operated by simply grasping the handles, as hereinbefore described, thereby dispensing with other means located exteriorly of the lock for thus actuating the bolt. The construction of the lock is such that very little labor is required to mount it in the door, as will readily be seen by referring to Figures 1 and 2, it being understood that the cylindrical casing 13 of the bolt is inserted into the hole or socket 14, bored into the door from the edge thereof, and a suitable opening 17 being provided transversely through the door to provide clearance for the slides 31 and 33, and the locking bar 69.

I claim as my invention:

1. In a door lock, a cylindrical bolt mounted for sliding movement in a door, oppositely disposed handles secured to the door in fixed relation, each handle having a lever pivotally mounted therein and each lever having one end adapted for swinging movement, slides operatively connecting said levers to said bolt whereby actuation of either lever will cause retraction of said bolt, to thereby permit opening of the door, and the inner end of one of said slides being forked, and the corresponding end of the other slide being received between the spaced legs of said forked end, thereby to prevent relative rotation of the bolt, when the latter is retracted.

2. In a door lock, a casing adapted to be mounted in a door, a bolt mounted for sliding movement in said casing, hollow handles secured to the door in fixed relation, a spring-actuated lever mounted in each handle and normally projecting outwardly therefrom, a slide operatively connected to the upper end of each lever and each having an operative connection with the locking bolt, whereby when either lever is actuated, the bolt is retracted to permit opening of the door, and means in one of said handles whereby the lever mounted therein is normally locked against movement.

3. In a door lock, a casing adapted to be mounted in a door, a bolt mounted for sliding movement in said casing, hollow handles secured to opposite sides of the door in fixed relation, a spring-actuated operating lever mounted in each handle and normally projecting outwardly therefrom, a slide operatively connected to the upper end of each lever and each having an operative connection with the locking bolt, whereby when either lever is actuated, the bolt is retracted to permit opening of the door, means in one of said handles whereby the lever mounted therein is normally locked against movement, and means in the other of said handles for releasing said normally locked slide.

4. In a door lock, a casing adapted to be mounted in a door, a bolt mounted for sliding movement in said casing, hollow handles secured to the door in fixed relation, a spring-actuated lever mounted in each handle and normally projecting therefrom in an inward direction, a slide operatively connected to the upper end of each lever and each having an operative connection with the locking bolt, whereby when either lever is actuated, said bolt is retracted to permit opening of the door, one of said slides having a forked end providing spaced legs between which the adjacent end of the other slide is supported, and means whereby the lever in one of said

handles may be locked against movement from either side of the door.

5. In a door lock, a cylindrical casing adapted to be mounted in a door, a bolt mounted for sliding movement in said casing and having its inner end forked to provide spaced legs, a roller mounted between said spaced legs and engaging the walls of the casing to thereby guide the inner end of the bolt, a pair of slides having their adjacent ends overlapped and supported between said spaced legs and provided with cam faces adapted to engage means on said bolt, a handle secured to each side of the door and each having a lever pivotally mounted therein, said levers being operatively connected to said slides whereby when one of said levers is actuated, the cam face of the slide connected thereto will engage the locking bolt and thereby cause retraction of the latter, whereby the door may be opened.

6. In a door lock, a cylindrical casing adapted to be mounted in a door, a bolt mounted for sliding movement in said casing and having its inner end forked to provide spaced legs, a roller mounted at the inner end of said bolt between the spaced legs thereof and engaging the walls of the casing to thereby guide the inner end of the bolt, a relatively smaller roller also mounted between the spaced legs of said bolt, a pair of slides having cam faces engaging said smaller roller and movable in opposite directions, a handle secured to each side of the door and each having a lever pivotally mounted therein, said levers being operatively connected to said slides whereby, when actuated, the cam faces thereof will engage said relatively smaller roller and retract the locking bolt to permit opening of the door, and means whereby the lever of one of said handles may be locked against movement to thereby secure the door against opening from one side thereof.

7. In a door lock, a bolt mounted for sliding movement in a door, face plates secured to opposite sides of the door, a handle secured to each side of the door, each handle having a longitudinal slot therein, pivoted levers mounted in said slots and closing the same, the upper ends of said levers having portions extending inwardly and engaging said face plates to thereby limit the inward swinging movements of the levers, slides connected to the levers and having their inner ends overlapped and operatively connected to said bolt, whereby when either lever is actuated, said bolt will be retracted to release the door, and means in one of said handles for normally locking the slide associated therewith.

8. In a door lock, a bolt mounted for sliding movement in a door, face plates secured to opposite sides of the door, a handle secured to each side of the door and seated upon said face plates, each handle having a longitudinal slot therein, spring-actuated levers pivotally mounted in said slots and closing the same, the upper ends of said levers having portions extending inwardly and engaging said face plates to thereby limit the inward swinging movements of the levers, a slide operatively connected to each lever and having their inner ends overlapped and operatively connected to said bolt, whereby when either lever is actuated, said bolt will be retracted to release the door, means in one of said handles for normally locking the slide associated therewith, and means in both of said handles whereby said last mentioned slide may be released from either side of the door.

9. In a door lock, a spring-pressed bolt in the door, a handle secured to the door in fixed rela-

tion, a spring-actuated lever mounted in the handle and normally projecting therefrom, a slide operatively connecting the lever to the bolt, whereby when the lever is actuated, the bolt is retracted to permit opening of the door, a member mounted for rotary movement and adapted to lockingly engage the slide to secure it against movement, thereby to lock the door, and means whereby said rotary member may be actuated by a key.

5. In a door lock, a spring-pressed bolt in the door, handles secured to the door in fixed relation, a spring-actuated lever in each handle, slides operatively connected to the levers and having their inner ends overlapped and operatively connected to the bolt, a notch in one of said slides, a member mounted for rotary movement and having a portion adapted to engage said notch, thereby to lock said notched slide against movement, and means in one of the handles whereby said rotatable member may be actuated by a key to lock or unlock said notched slide.
